HOLDER FOR ROLL TOILET TISSUE

Francis J. Moore, Minneapolis, Minn.

Application June 19, 1951, Serial No. 232,412

4 Claims. (Cl. 242—55.2)

1

My present invention relates to improvements in toilet tissue holders and, more particularly, for a holder for a roll of toilet tissue.

One of the objects of this invention is to provide a novel holder for removably holding a roll of toilet tissue in a recess, such as a recessed tile set in a wall.

Another object of the invention is to provide such a holder for holding a roll of toilet tissue that will freely rotate on the holder when the tissue is pulled to unwind the same from the roll, but which will frictionally hold the roll from spinning in case the tissue is given a quick pull and thereby unwinding a surplus of the tissue, resulting in waste.

A further object of this invention is to provide novel means for holding the holder from turning in the recess in which it is mounted when the tissue is pulled to unwind the same from the roll.

A still further object of the invention is to provide a novel holder that can be adjusted to move a roll of toilet tissue mounted thereon either forwardly or backwardly in the recess in which the holder is mounted.

Other objects of the invention will be apparent from the following description, reference being had to the drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is a front elevational view of the improved holder mounted in a recessed tile to be set in a wall;

Fig. 2 is a view in plan with some parts broken away and sectioned; and

Fig. 3 is a detail view partly in elevation and partly in section taken on the line 3—3 of Fig. 2.

The numeral 4 indicates a tile to be set in a wall and having a recess 5 and also having in its side members 6 within the recess 5 a pair of opposing shallow cylindrical seats 7.

Referring now in detail to the invention, the numeral 8 indicates a round shaft that is longitudinally divided at its axis, and the two semi-circular sections thereof are detachably connected by a pair of nut-equipped bolts 9 that extend through aligned holes in said sections. A round rod 10 that extends parallel to the shaft 8 has its intermediate portion offset in the form of a yoke 11. The transverse member 12 of the

2

yoke 11 is parallel to the end portions of said rod and the side members 13 of the yoke 11 are perpendicular to its transverse member 12. The yoke side members 13 extend through bores 14 formed in the opposing sides of the two sections of the shaft 8 at the axis of said shaft. The bolts 9 hold the sections of the shaft 8 clamped onto the yoke side members 13 and said side members when endwise adjusted in the bores 14.

One end of the shaft 8 is mounted in one of the seats 7, and a cylindrical sleeve 15 slidably mounted on the other end portion of the shaft 8 extends into the other seat 7. A coiled spring 16, encircling the shaft 8 inwardly of the sleeve 15, is compressed between an annular flange 17 on the inner end of said sleeve 15 and the adjacent yoke side member 13 and yieldingly holds said sleeve projected into its seat 7. A pin 8' in the shaft 8 extends through a longitudinally extended slot 15' in the sleeve 15 and limits the projecting movement of said sleeve by the spring 16.

Obviously, by retracting the sleeve 15 against the tension of the spring 16, the same will be removed from its seat 7 and thus permit the holder to be removed from the recess 5.

A shoe 18, of rubber or other suitable material, secured on one end portion of the rod 10 engages the face of the adjacent tile side member 6 and holds the shaft 8 from turning in the seats 7.

A roll of toilet tissue 19 wound on a cylindrical paper core 20, indicated by broken lines, is mounted on the improved holder.

Before the holder is mounted in the recess 5, the same is inserted endwise into the core 20.

35 The yoke transverse member 12 and the end portions of the rod 10 engage the core 20, intermediately at diametrically opposite points and support the same to turn thereon when the tissue is pulled to unwind the same from the roll 19. 40 However, the friction contact between the holder and the core 20 is sufficient to prevent the roll from spinning in case the tissue is given a quick pull.

45 The drawing illustrates a commercial form of the invention, but it will be understood that the same is capable of certain modifications as to details of construction, arrangement and combination of parts within the scope of the invention herein disclosed.

50 What I claim is:

1. In a holder of the class described, a shaft having on one end a spring-projected extension, and a rod offset at its intermediate portion in the form of a yoke having a transverse portion and

two side members, said side members extending transversely of the shaft and secured thereto.

2. The structure defined in claim 1 in which the yoke side members are secured to the shaft for endwise adjustment.

3. The structure defined in claim 1 in which the shaft is longitudinally divided at its axis, said shaft having two transverse bores in the opposing sides of the shaft through which the yoke side members extend for endwise adjustment, and means connecting the members of the shaft and frictionally clamping the same onto the yoke side members.

4. The combination with a wall member having a recess, said member having at the sides of the recess a pair of opposing bore-like seats, of a shaft having on one end portion a spring-projected extension, said extension and the opposite end portion of the shaft being removably held in

said seats, a rod substantially parallel to the shaft, the intermediate portion of the rod being offset in the form of a yoke comprising a transverse member and two side members, said side members extending transversely of the shaft and secured thereto, said rod having on one end portion a shoe engaging said recessed member and holding the shaft from turning in the seats.

10
